MARTIN HEMLEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

MOTOR-DRIVEN SEWING MACHINE.

Application filed May 19, 1925. Serial No. 31,294.

This invention relates to motor driven sewing machines and more particularly to sewing machines of the type having a small individual driving motor mounted on the 5 sewing machine frame and connected directly to the sewing machine balance-wheel. The motor of such an outfit is customarily of the series wound type and is controlled through a treadle- or knee-operated rheostat connected in series with the motor. Motors of the high-speed type are customarily used for this work to gain the necessary power to drive the machine in a motor 10 of small size and weight; light weight and 15 ready portability of the outfit being an important desideratum.

Heretofore the motor-shaft has been fitted with a small pulley which has been connected to a larger pulley on the sewing machine balance-wheel, thereby effecting the necessary speed reduction to drive the machine at normal speed.

An undesirable characteristic of an outfit such as above described is that the motor 25 will not run steadily at low speeds or when the rheostat is shifted to include considerable resistance in the motor circuit. For certain classes of work with sewing machines, such as embroidery, it is essential 30 that the machine run steadily at a very low speed so that the operator can shift the work between stitches and have time to accurately position the work for each needle-thrust. The unsteady running characteristics of the 35 above described prior motor-driven sewing machines at low speeds is found to be due very largely to the bearing friction on the motor-shaft caused by the side thrust on the small pulley of the motor. Further, in a belt-driven outfit, the sharp degree of flexing of the belt required when running over a small pulley increases the belt tension required to prevent slippage, and small variations in the load on the motor, such as caused by irregularities in the belt, have considerable effect 45 upon the speed of the motor, sometimes causing it to stop and then as the resistance of the controller is reduced, to jump ahead at too great a speed for embroidery.

50 The present invention has for an object to provide a sewing machine with a motor attachment and motor controller whereby the machine may at the will of the operator

be steadily driven at normal sewing speeds or at low speeds such as required for embroidery.

To the attainment of the ends in view the motor has mounted on its frame a comparatively large pulley having an internal gear with which meshes a small pinion fixed 60 to the motor-shaft. The motor is mounted on the sewing machine frame and the large pulley is connected directly to the sewing machine balance-wheel, preferably by means of a belt. By these means, the side thrust 65 on the driving pulley necessary to prevent slippage is considerably reduced; the wrap of the belt around the driving pulley is increased and the speed of the motor and machine may be nicely controlled at both normal running and low speeds by means of the usual rheostat connected in series with the motor; a result not heretofore attained in a light weight motor-driven sewing machine outfit.

In the accompanying drawings illustrating a preferred embodiment of the invention, Fig. 1 is a rear end elevation of a sewing machine and motor driving device embodying the invention. Fig. 2 is a fragmentary 80 horizontal section through the motor and sewing machine standard. Fig. 3 is a vertical section through the driving pulley. Fig. 4 is a perspective view of the motor-frame. Fig. 5 is a perspective view of a 85 guard or disk cap for the gear drive. Fig. 6 is a perspective view of the supporting stud for the driving pulley and Fig. 7 is a diagram of the electric circuit for the motor and controller.

The sewing machine comprises the usual bed 1 and bracket-arm standard 2 and main-shaft 3 carrying the usual balance-wheel 4 having the belt-groove 5. Secured to the seat 6 on the standard 2 by means of the screw 7 is the motor-bracket 8 having a slot 8' through which the screw 7 passes, such slot permitting a vertical shift or adjustment of the bracket 8 for belt-tightening purposes.

Secured to the bracket 8 by the screw 9 is the motor-frame 10 in which is journaled the motor-shaft 11, one end of which projects through the bearing aperture 12 in the motor-frame and has fixed thereto the pinion 13.

Journalized on the stud 14 fixed in the aperture 15 in the motor-frame between the motor-shaft 11 and the standard 2 is the relatively large driving pulley 16 which is cuffed out to fit over the pinion 13 and is formed with an internal gear 17 meshing with the pinion 13. The driving pulley 16 is connected to the sewing machine balance-wheel, such connection being preferably a belt 18 which is led around the pulleys 5 and 16, both of which are of comparatively large diameter and do not require the belt to flex sharply.

A dust-guard 19 having a clearance aperture 20 for the motor-shaft is secured to the motor-frame by means of the stud 14 which passes through the aperture 20' in the dust-guard and has a collar 21 between its ends for holding the guard 19 to the motor-frame. The stud 14 is hollow, Fig. 3, and is provided with an internal wick 22 for conducting lubricant from the oil-cup 23 to the bearing for the pulley 16.

The motor is of the usual series wound type as indicated in Fig. 7 and is connected in series with the usual treadle or knee-operated rheostat.

By use of the present construction the machine may be operated at the usual running speeds and may also be nicely controlled at low speeds such as required for embroidery. The motor is of the light weight high-speed type controlled by the usual rheostat and hence use of the present improvement entails no sacrifice of the de-

sirable characteristics of prior sewing machine motor drives.

The bracket 8 is preferably constructed substantially in accordance with the disclosure of my Patent No. 1,520,949, dated December 30, 1924.

It will be seen that the comparatively large pulley 16, being journalized between the vertical plane of the motor-shaft 11 and sewing machine standard 2, does not extend rearwardly beyond the motor-frame or rearward edge of the bed 1 and thus does not interfere with the housing of the machine under the cover of the usual carrying case or in the usual drop-head cabinet.

Having thus set forth the nature of the invention, what I claim herein is:—

In a motor driving attachment for sewing machines, the combination with an electric motor having a frame and motor-shaft, said frame having a shaft bearing aperture and a stud-pin aperture spaced from said shaft bearing aperture, of a stud-pin secured in said stud-pin aperture and formed with a collar between its ends, a driving pulley journaled on said stud-pin and having an internal gear, a pinion fixed to the motor-shaft and meshing with said internal gear, and a dust cap secured to the motor-frame by the collar on said stud-pin and covering said internal gear and pinion.

In testimony whereof, I have signed my name to this specification.

MARTIN HEMLEB.
